ILLUMINATING APPARATUS

Lloyd A. Patton, East Orange, and Ray C. Smith,
Rutherford, N. J., assignors to Western Electric Company, Incorporated, New York, N. Y.,
a corporation of New York

Application March 13, 1940, Serial No. 323,726

1 Claim. (Cl. 240—2)

This invention relates to illuminating apparatus, and more particularly to illuminating apparatus for use in assembling or adjusting articles.

In assembling and adjusting certain types of articles or apparatus, for example, relays used in the art of telephony, it has been found that more than the standard overhead light is necessary in properly illuminating the field of work without interfering with the operator's sight. Although light rays projecting on the work from above are satisfactory when the portions of the work requiring the attention of the operator are in the path of such rays, but when additional portions of the work at the sides or bottom thereof require the operator's attention such light rays in some instances may be found not to be completely satisfactory.

An object of the invention is to provide a simple, efficient and highly practical apparatus for illuminating articles.

With this and other objects in view, the invention comprises an illuminating apparatus having a hollow work support, upon which tubular uprights are mounted, for supporting a lamp over the work, positioned on the work support, and also having a lamp disposed therein beneath a mesh covered opening where louvers are disposed to direct the light rays from the second-mentioned light to the work and away from the operator.

Other objects and advantages will be apparent from the following detailed description when taken in conjunction with the accompanying drawings, wherein:

Fig. 1 is a front elevational view of the apparatus, portions thereof being shown in section;

Fig. 2 is a fragmentary plan view of the lower portion of the apparatus taken substantially along the line 2—2 of Fig. 1;

Fig. 3 is a side elevational view of the apparatus, and

Fig. 4 is an enlarged fragmentary sectional view taken substantially along the line 4—4 of Fig. 2.

Referring now to the drawings, numeral 10 designates a hollow support of the general contour and structure shown. In the present instance the support is formed of sheet metal reenforced by suitable angle members as illustrated in Fig. 1. Spaced members 11 and 12 are mounted upon the upper surface of the support near the rear edge thereof and project upwardly to removably support an article 14 therebetween.

An elongate aperture 16 is formed in the support 10 in the upper portion thereof, extending

substantially the full width of the support and disposed adjacent the forward edge or surface 17 thereof. A lamp 18, which in the present instance is a fluorescent lamp, substantially equal in length to the aperture 16 is disposed in the support adjacent the opening but not in true alignment therewith. It will be observed, by viewing Figs. 2, 3 and 4, that the lamp is disposed slightly to the front of the vertical center 10 of the aperture 16. Suitable brackets 20 for the lamp 18 are mounted in the support and are provided with the necessary electrical contacts to include the lamp in an electrical circuit controlled by a switch 21 when a connecting plug 22 is inserted in a suitable socket of a supply circuit (not shown).

A screen 24 is mounted across the aperture 16 within the support to eliminate the possibility of particles dropping into the support and on the lamp. Above the screen is disposed a plurality of louvers 25 spaced as illustrated in Figs. 3 and 4 and extending in directions parallel with each other to control rays of light given by the lamp, as will be more fully described hereinafter.

The under surface of the support 10 has dome-like members 26 for resting on a suitable bench or table when the apparatus is in use. The upper portion of the support continues upwardly and rearwardly at an angle as illustrated at 27 in Figs. 1 and 3, to eliminate the possibility of articles or tools used in the adjustment and assembly of articles from dropping from the support.

Substantially U-shaped tubular uprights 30 have their lower ends extending into the support 10 through apertures in the rear wall thereof, where they are secured against displacement by suitable means such as brackets 31, while the upper ends thereof extend forwardly to support a lamp unit indicated generally at 32. The lamp unit comprises a reflector 34 having suitable brackets 35 mounted therein for removably supporting a lamp 36 and electrically including the lamp in a circuit controlled by a switch 37 when the plug 22 is connected with a suitable source of electrical energy. The electrical conductors for the circuit including the lamp 36 may be used in either or both uprights 30 extending from the support 10 to the brackets 35. The lamp 36 in the present instance is of the fluorescent type, extending longitudinally of its shade 34 between the brackets 35 while the shade 34 has a hollow inner contour that will direct rays of light given by the lamp 36 downwardly toward the article 14 supported by the member 11. In order to eliminate

the possibility of any of these rays of light from being directed toward the operator's eyes, a shield 38 is supported by and extends longitudinally of the forward and lower end of the shade 34.

When the apparatus is in use in assembling or adjusting articles supported by the members 11 and 12, both lamps 18 and 36 may be illuminated by actuating the switches 21 and 37, respectively, to complete the electrical circuits of these lamps. The lamps 36 will give rays of light which will be controlled by the reflector 34 to reflect the rays downwardly toward the article 14 and completely as well as uniformly cover the article throughout its length with uniform light so that the operator may readily observe any part of the article on which he desires to work.

Referring now to the lamp 18, it will be observed that the rays of light given thereby will be directed through the aperture 16 and controlled by the louvers 25, the lamp 18 extending the full length of the aperture giving uniform rays of light for the full length thereof. These rays of light are directed upwardly at an angle toward the article 14 and away from the forward edge 17 of the support. The purposes for directing the rays of light in this direction are to uniformly cover the article throughout its length with the rays of light so that the operator may readily observe any part of the article throughout its length without any variation in the light from the different parts thereof, and further to keep the rays of light away from the operator's eyes. When an operator is required to work on elongate articles it is a strain on his eyes if all parts requiring his attention are not properly and uniformly illuminated. For example, if the parts at the center are illuminated more than those at the ends a constant change takes place in the focusing effect of the operator's eyes as the operator shifts his glance from one position to another. When this is continued throughout a working day there exists considerable strain on

the eyes of the operator in addition to the reduction in his efficiency caused by improper illumination. When such an article is illuminated uniformly throughout its length on all surfaces requiring the attention of the operator, there is no repeated change in the function of the operator's eyes as they move their glance from one position on the article to another.

The embodiment of the invention herein disclosed is illustrative only and may be widely modified and departed from in many ways without departing from the spirit and scope of the invention as pointed out in and limited solely by the appended claim.

15 What is claimed is:

An illuminating apparatus comprising a hollow support having walls including a front wall and a top wall, the latter having an elongate aperture therein spaced back from the front wall, spaced members mounted upon the top wall externally of the support to support an elongate article at a spaced position above the support back of the aperture and parallel therewith, a fluorescent lamp disposed in the support adjacent the aperture and parallel therewith to give uniform rays of light through the aperture throughout the length thereof, louvers disposed in the housing and extending longitudinally of the aperture parallel therewith and with the lamp and the article to direct the rays passing through the aperture uniformly away from the front wall and directly to the front and bottom portions of the article, an upright mounted on the support, a second fluorescent lamp mounted adjacent the upper end of the upright and parallel with the article to give uniform light rays above and closely adjacent the article, and means to direct the light rays of the second lamp uniformly downwardly to the top portion of the article.
